UNITED STATES PATENT OFFICE

167,254

CARTON HOLDING PITCHER

Frank M. Cherry, Montebello, Calif.

Application May 28, 1951, Serial No. 15,332

Term of patent 3½ years

(Cl. D44—21)

To all whom it may concern:

Be it known that I, Frank M. Cherry, a citizen of the United States, residing at Montebello, California, have invented a new, original, and ornamental Design for Carton Holding Pitcher, of which the following is a specification, reference being had to the accompanying drawing, which forms a part thereof, and in which drawing:

Fig. 1 is an exploded side elevational view of a carton holding pitcher, showing my new design;

Fig. 2 is a rear elevational view;

Fig. 3 is a top plan view;

Fig. 4 is a vertical sectional view taken on the line 4—4 of Fig. 2; and

Fig. 5 is a cross-sectional view thereof taken on the line 5—5 of Fig. 1.

I claim:

The ornamental design for a carton holding pitcher, substantially as shown.

FRANK M. CHERRY.
